UNITED STATES PATENT OFFICE.

JAMES HAYTON, OF SALT LAKE CITY, UTAH TERRITORY.

MECHANICAL MOVEMENT.

SPECIFICATION forming part of Letters Patent No. 435,826, dated September 2, 1890.

Application filed April 16, 1890. Serial No. 348,073. (No model.)

To all whom it may concern:

Be it known that I, JAMES HAYTON, of Salt Lake City, in the county of Salt Lake and Territory of Utah, have invented a new and Improved Mechanical Movement, of which the following is a full, clear, and exact description.

The invention relates to mechanical movements for converting reciprocating motion into rotary motion, and its object is to provide a new and improved mechanical movement for said purpose, which is simple and durable in construction, very effective and positive in operation, and transmits the power without any undue friction or lost motion, avoiding all dead-centers.

The invention consists of certain parts and details and combinations of the same, as will be hereinafter fully described, and then pointed out in the claim.

Reference is to be had to the accompanying drawings, forming a part of this specification, in which similar letters of reference indicate corresponding parts in all the figures.

Figure 1 is a side elevation of the improvement in a central position. Figs. 2 and 3 are like views of the same in the end positions, and Fig. 4 is a transverse section of the same on the line $\alpha\alpha$ of Fig. 1.

The improved mechanical movement A is provided with a suitably-constructed base-plate B, adapted to be secured to the frame of the machine on which the mechanical movement is to be applied. On top of the base-plate B is arranged a longitudinally-extending guideway C, to the sides of which are secured upwardly-extending plates D, supporting at their upper ends a second guideway E, extending parallel to the guideway C. In the guideways C and E is fitted to slide longitudinally a frame F, provided with the two sides F' and F² and the ends F³ and F⁴, of which the latter are provided with heads F⁵ and F⁶, in one of which is secured a rod G by means of a pin H. The rod G is connected with the machinery the reciprocating motion of which is to be converted into rotary motion. The sides F' and F² fit into the guideways E and C, respectively, and they are provided at their opposite edges with rack-teeth F⁷ and F⁸, respectively, three only in number, as shown in the drawings. The teeth F⁷

and F⁸ are adapted to be alternately engaged by teeth I, formed on a segmental wheel J, secured by its hub J' on a transversely-extending shaft K, mounted to turn in suitable bearings L, and also provided with a fly-wheel N and the usual pulley O, adapted to be connected with suitable machine to be driven. The inner edges of the ends F³ F⁴ of the frame are parallel with each other and at right angles to the upper and lower toothed sides F' F². The said inner edges of the ends F³ F⁴ are centrally recessed, as shown at F⁹ F¹⁰, thereby forming a pair of shoulders F¹¹ F¹² and F¹³ F¹⁴ at the ends of the frame, the inner faces of each pair of shoulders lying in the same vertical plane. It will be noticed that the end edges J² J³ of the toothed segment are radial to its axis and at an obtuse angle to each other.

The operation is as follows: When a reciprocating motion is imparted by the rod G to the frame F a continuous rotary motion is transmitted by the toothed segment J to the shaft K in the following manner: When the frame F slides in the direction of the arrow a' and is in the position shown in Fig. 1, then the middle tooth of the teeth on the side F' stands in the middle of the segmental gear-wheel J, and by the action of the latter it is turned in the direction of the arrow b' . (See Fig. 1.) When the frame F nears the end of its stroke, the segmental gear-wheel assumes the position shown in Fig. 2—that is, the last tooth on the side F' is about to be disengaged from one end tooth of the segmental gear-wheel J, which, by its other end tooth, is about to be engaged by the first tooth of the other side F². When the frame in its movement to the right nears the end of the stroke, the parts will be in the positions shown in Fig. 2, and the shoulder F¹³ will engage the edge J³ of the segment J, and as the frame continues to move to the right will disconnect the last tooth at the upper end of the segment from the left-hand tooth of the upper series F⁷ and throw the edge J² against the shoulder F¹⁴, so as to bring the last tooth at the lower end of said segment into position for action by the lower left-hand tooth F⁸ and just as the frame begins its return-stroke to the left. When the frame reaches the end of its left-hand stroke, the shoulder F¹² will act

on the edge J^3 of the segmental gear J and throw its lower end tooth out of engagement with the lower right-hand tooth F^8 and its edge J^2 against shoulder F , so that the top tooth I of the segment will be brought into position just as the frame again begins its right-hand stroke, and so on continuously. Thus it will be seen that a continuous rotary motion is imparted to the segmental gear-
wheel J and its shaft K by the reciprocating movement of the frame F in the guideways C and E . It will thus be seen that the reciprocating motion is converted into a rotary motion without the use of pitmen and crank-arms and without any lost motion whatever. It will further be seen that the frame F , by means of the heads F^5 and F^6 , can be readily attached to right or left handed machines, as the said heads are adapted to receive rod G coming from the right or left.

Having thus described my invention, what I claim as new, and desire to secure by Letters Patent, is—

The herein - described mechanical movement, which consists in the upper and lower

parallel guideways, a reciprocating frame F mounted therein and provided with a central rectangular opening having rack-teeth F^7 F^8 on its upper and lower walls and vertically-aligned shoulders F^{11} F^{12} and F^{13} F^{14} on its ends, recesses F^{10} F^9 separating the shoulders of each pair, the continuously-rotatory shaft K , provided with a segmental gear J , the end edges or shoulders J^2 J^3 of which are radial to the shaft and at an obtuse angle to each other, whereby when one of the frame-shoulders engages one of the end segments, edges, or shoulders the segment-tooth next thereto will be thrown out of engagement with the rack, and the other end, edge, or shoulder of the segment will be thrown against the other one of the same pair of frame-shoulders to bring the adjacent gear-tooth into mesh with the adjacent end tooth of the opposite rack, substantially as set forth.

JAMES HAYTON.
